(57) CLAIM

The ornamental design for an oven glove, as shown and described.

DESCRIPTION

FIG. 1 is a top plan view of one embodiment of an oven glove, showing one version of my new design;

FIG. 2 is a bottom plan view of the embodiment of FIG. 1; FIG. 3 is a left end view of the embodiment of FIG. 1, the opposite (right) end view being a mirror image thereof; FIG. 4 is a section view of the embodiment of FIG. 1, taken from the direction 4—4, and illustrating the thickness of the quilted fabric of my new design;

FIG. 5 is a top plan view of another embodiment of an oven glove, showing another version of my new design;

The broken lines shown on the oven glove in the drawing are understood to represent stitching.
